DIE

Alwin Deichmiller and Edmund F. Shalla, Pasadena, Md., assignors to Western Electric Company, Incorporated, New York, N. Y., a corporation of New York

Application June 19, 1948, Serial No. 34,003

3 Claims. (Cl. 164—118)

1

This invention relates to dies, and more particularly to sectional dies for material punching operations.

An object of the invention is the provision of new and improved dies.

A further object of the invention is to provide new and improved sectional dies for material punching operations.

Another object of the invention is to provide new and improved sectional dies which are held tightly together on platens.

A die illustrating certain features of the invention may include a sectional die element having a portion tapering from one face thereof to the opposite face thereof, and a clamp being provided with arms complementary to said portion of the die element, whereby the sections of the die element may be wedged together by the clamp.

A complete understanding of the invention may be obtained from the following detailed description of a die forming a specific embodiment thereof, when read in conjunction with the appended drawing, in which:

Fig. 1 is a plan view of a die forming one embodiment of the invention, and

Fig. 2 is a fragmentary, vertical section taken along line 2—2 of Fig. 1.

Referring now in detail to the drawing, a die 10 is provided with a pair of die apertures 12 and 14 formed in sections 16, 17 and 18, which are held against longitudinal movement relative to one another by keys 20 and 22. Cap screws 24—24 threaded into tapped bores 26—26 formed in a platen 28 secure the die 10 to the platen 28 after the sections 16, 17 and 18 of the die 10 are wedged tightly together by the action of dovetailed clamps 30—30, which are provided with wedge surfaces 32—32 acting against wedge surfaces 34—34 formed on the sections 16 and 18 of the die 10. That is, there is a compound taper on the clamps and the die so that the clamps cannot work free of the die accidentally. The die holds the clamps against the platen, and the dovetailing prevents the clamps from sliding off the ends of the die.

The die 10 and the clamps 30—30, which are movable with the die 10 as a unit, may be released from the platen 28 merely by unscrewing the cap screws 24—24. The die 10 may be disassembled from the clamps 30—30 merely by tapping the clamps 30—30 or the die sections 16 and 18 in directions such as to lessen the wedging action between the clamps 30—30 and the die 10. Hence, the die 10 may be easily disassembled for maintenance operations thereon that may be needed.

The die sections 16, 17 and 18 are easily assembled in close relationship merely by tapping the die sections into the clamps 30—30. The die and the clamps then are mounted on the platen,

2

and the die sections 16 and 18 are bolted to the platen 28. The clamps 30—30 force the die sections 16 and 18 tightly against the die section 17 so that the sections 16, 17 and 18 fit tightly together and are always spaced the same after each maintenance operation in which they are removed from the clamps 30—30 and replaced therein.

A clamp, such as the clamps 30—30, may be used to repair a cracked die merely by forming portions complementary to the compoundly tapered clamp at the edge of the die and bracketing the crack in the die so that the clamp is locked to the die and presses together the portions of the die on opposite sides of the crack.

What is claimed is:

1. A die, which comprises a platen, a sectional die having male dovetailed end portions bracketing the juncture between the elements of the sectional die, said die having a noncircular die opening intersecting the juncture of the elements thereof, a pair of clamps having female dovetailed portions complementary to the dovetailed portions of the die for clamping together the sectional elements of the die, and means for securing the die to the platen, the dovetailed portions of the clamps and the die being wedge-shaped in planes substantially transverse to the plane of the die and in such directions that the die locks the clamps to the platen.

2. A die, which comprises a platen, a die element having a split therein extending from one end to the other end, said die element having male dovetailed portions bracketing the ends of the split and also being provided with a non-circular die opening intersecting the split therein, a pair of clamps having female dovetailed portions complementary to the male dovetailed portions of the die element for clamping together the portions of the die element on opposite sides of the split, a key for keying the portions of the die element against movement relative to one another along the split, and means for securing one of the die element and the pair of clamps to the platen, the dovetailed portions of the die element and the clamps being wedge-shaped in a plane substantially transverse to the plane of the die and the direction of wedging being such that the one of the die element and the pair of clamps that is secured to the platen locks the other to the platen, the clamps and the die element being so constructed and arranged that there is clearance between the ends of the arms of the clamps and the die element and the ends of the die element abut the portions of the clamps between the arms thereof when the clamps are in locking positions on the die element.

3. A die, which comprises a platen, a die element having a split therein extending from one

end to the other end, said die element having male dovetailed portions bracketing the ends of the split and also being provided with a noncircular die opening intersecting the split therein, a pair of clamps having female dovetailed portions complementary to the male dovetailed portions of the die element for clamping together the portions of the die element on opposite sides of the split, a key for keying the portions of the die element against movement relative to one another along the split, and means for securing the die element to the platen, the dovetailed portions of the die element and the clamps being wedge-shaped in a plane substantially transverse to the plane of the die and the direction of wedging being such that the die element locks the clamps to the platen, the clamps and the die element being so constructed and arranged that there is clearance between the ends of the arms of the clamps and the die element and the ends of the die element abut the portions of the clamps between

the arms thereof when the clamps are in locking positions on the die element.
